[57] CLAIM

The ornamental design for an illuminated mirror case, substantially as shown and described.

DESCRIPTION

FIG. 1 is a top plan view of an illuminated mirror case showing my new design;

FIG. 2 is a bottom plan view thereof;

FIG. 3 is a top plan view thereof in the open position;

FIG. 4 is a front elevational view thereof;

FIG. 5 is a rear elevational view thereof; and

FIG. 6 is a top plan view of a modified form of the illuminated mirror case shown in FIG. 1 showing the same in the open position.
